(57) **CLAIM**

The ornamental design for a zig-zagged swept wing kite, as shown and described.

DESCRIPTION

FIG. 1 is a top perspective view of a zig-zagged swept wing kite showing my new design;

FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a rear view thereof.

In the drawings, the broken lines depict portions of a zig-zagged swept wing kite that form no part of the claimed design.

1 Claim, 5 Drawing Sheets# US D873,350 S
